SIZING MACHINE

Milton F. May, Saginaw, Mich.

Application October 9, 1947, Serial No. 778,845

6 Claims. (Cl. 78—13)

1

This invention relates to a machine for accurately sizing and finishing the I. D., O. D. and length of oilless bearings or bearings of a porous nature capable of absorbing lubricants.

One of the prime objects of the invention is to design a very simple, practical, and efficient machine for sizing bearings in which all of the working parts are concentric to the I. D. sizing ram and in which the I. D., O. D., and length sizing are performed in proper sequence, without removal of the work from the machine, so that the same center is maintained at all times, making for extreme accuracy in production.

Another object is to provide a sizing machine which occupies a limited floor space and by means of which maximum production is obtained with a minimum of labor and in which the sizing head can be disposed in either a horizontal or vertical position, so that it can be designed to best suit the work, promoting greater efficiency and economy of operation.

A further object is to provide a sizing machine in which all die head moving parts are in the punch section only so that true concentricity is obtained.

Still a further object is to design a sizing machine of simple, sturdy, and practical construction which can be readily manufactured and assembled, and which can be designed to meet any reasonable production requirement.

With the above and other objects in view, the present invention consists in the combination and arrangement of parts, hereinafter more fully described, illustrated in the accompanying drawings, and more particularly pointed out in the appended claims, it being understood that changes may be made in the form, size, proportion, and minor details of construction, without departing from the spirit, or sacrificing any of the advantages of the invention.

In the drawings:

Fig. 1 is a front-elevational view of my improved sizing machine.

Fig. 2 is an end-elevational view thereof.

Fig. 3 is an enlarged, fragmentary, longitudinal, sectional view through one of the cylinders, the loading, feeding mechanism, etc. being omitted, the mechanism being shown in position at the end of its inward stroke.

Fig. 4 is a top plan view thereof.

Fig. 5 is a view similar to Fig. 3 showing also the block and loading mechanism, the ram, etc. being shown at the end of its outward stroke.

Fig. 6 is an end view showing also the feed trough, the loading member being shown at the end of its downward stroke.

2

Fig. 7 is a fragmentary, sectional view showing the mechanism retracted.

Fig. 8 is a perspective detail view of the loading member.

Fig. 9 is an isometric view showing the article through extension.

Fig. 10 is a view similar to Fig. 6 showing the loading member at the end of its upward stroke.

The sizing machine is preferably hydraulically operated, and comprises a housing 10 having a flat top section 11 on which a plurality of die heads H are mounted, each head being of identical design and construction, so that a description of but one head will suffice for all.

15 The housing 10 can be of any desired shape or design, and the heads can be mounted either horizontally as shown or vertically if desired, and the hydraulic actuating means and control 12 and 13 respectively are of standard design, and I shall not show or describe them in detail as they form no part of the instant application which is directed to the sizing head and loading means only.

20 Each of the heads H comprises a cylinder block 14, which blocks are mounted in opposed relation, each block having end caps 15 and 16 respectively generally rectangular in shape, which are secured in position by means of stay bolts 17, and openings 18 are provided as usual for securing the head to the table.

25 A centrally disposed opening 19 is provided in the end cap 15 of the head and slidably accommodates the stem 20 of a hollow ram body 21 which is slidably mounted for reciprocating movement in the cylinder 14, and a longitudinally disposed I. D. sizing punch 22 has threaded engagement with the end wall of the ram body and is movable with said ram.

The end cap 16 is shaped similar to the cap 15 and is bored to accommodate the cylinder 14 in 30 which the die holder 23 is slidably mounted, said holder being turned to reduced diameter as at 24 and a shoulder 25 is provided on the inner end of the die holder as shown, said shoulder having sliding engagement with the hollow bored section 26 of the ram body 21.

A stripper shoe 27 is secured on the inner end of the ram body 21 by means of screws 28 and slides on the reduced section 24 of the die holder and engages the shouldered end 25 for imparting movement to said die holder on the return stroke of the ram.

35 The die holder 23 is internally bored as shown to accommodate a stripper and length sizing member 29, the exterior of the stripper being shouldered as at 30, said shoulder butting against 40

45 50 55

the shouldered section 31 of the die holder when the mechanism is in retracted position as shown in Fig. 3. The member 29 is moved forwardly by the ram 21 engaging the rear end thereof near the end of its forward stroke and is retracted upon engagement of the shoulders 33 and 31 during the return stroke. Stationary pins 32 extend through suitable openings in the ram body and the ram is slidable with relation thereto, one end of the pins bearing against the hardened insert I while the opposite ends butt against the one end of the length sizing member 29 as usual.

The head 33 of the length adaptor D is rigidly mounted in the shouldered end 35 of the stripper 29, said adaptor including a stem 36 which closely fits and slides on the I. D. punch 22, the stem 36 projecting into the bore 37 of the O. D. die adaptor 38, which is in turn mounted in the bored shouldered end of the die holder 23 and secured in position by means of setscrew 39.

A stationary guide block 49 is mounted on the top section 11 of the housing 10 at a point closely adjacent to and in longitudinal alignment with the cylinder block H (see Fig. 5 of the drawings), said block having a bored passage 41 opening into an enlarged bore 42 in which a centrally bored length adaptor 43 is mounted and held by means of a setscrew 44, the stem 45 of the adaptor closely fitting the bore 37 of the die adaptor 38 and being slidable therein, the tapered end of the punch 22 being in horizontal alignment with and projecting into and through the adaptor 43 as the mechanism is actuated and as indicated in Fig. 7 of the drawings.

The loading and ejecting mechanism comprises an angularly disposed loading member 46 (see Figs. 6, 7, 8 and 10 of the drawings) disposed at substantially right angles to the path of travel of the ram 21; this is formed with a stem 47 the member being actuated by a solenoid (not shown) and is mounted for substantially vertical reciprocatory movement in gibs 48 provided as shown. A shouldered stop 49 is formed on the loading member 46 for engagement with an abutment member 50 provided on the table (see Fig. 6 of the drawings), this member serving as a stop and horizontal adjustment for the loading member and further controls the length of stroke.

A shoulder 51 is provided on the one side of the loading member 46 and an upwardly projecting pin 52 is mounted on the upper face of said shoulder.

A vertically disposed stop plate 53 is mounted on the inner face of the shoulder 51 by means of screws 54, and a notched opening 55 is provided in the upper end of said plate and for a purpose to be presently described.

The face 56 of the loading member 46 is longitudinally slotted as at 57 (see Figs. 6, 7 and 10) and a vertically disposed inverted, T-shaped ejector member 58 is mounted to slide longitudinally therein, this ejector being slotted as at 59 and a screw 60 extends through said slot and is threaded into the end of the die holder 23. Obviously, the member 58 moves up and down with the member 46, but is slidable longitudinally relative thereto when the die holder 23 moves forwardly to the position shown in Fig. 5.

A stop 61 is mounted on the end wall of the die holder 23 and serves to limit the downward travel of the bearings as they are fed to the machine.

An inclined trough 62 leads to the loading mechanism of each head, the end of the trough terminating at the stop plate 53, and the bear-

ings B are fed to the trough in any desired manner.

A short trough section 63 is mounted on the face of the die adaptor 38 in direct alignment with the trough 62 (see Fig. 9) so that incoming bearings feed from the trough 62 through the section 63 and thence roll against the stop 61 to center the bearing B in the mechanism.

A pin opening 64 is provided in the bottom wall of the trough 62 and as the ejecting mechanism is actuated, the control member 53 moves upwardly to position to permit a bearing B to roll from the trough 62 into the section 63 (see Fig. 10 of the drawings) and thence against the stop 61, the pin 52 extending through opening 64 and permitting but one bearing at a time being fed into the mechanism.

A plate 65 is mounted on the end of the die holder 23 and an opening 65a is provided adjacent the edge thereof, a longitudinally disposed pin 66 being mounted on the end cap 16 and is slidable in said opening to prevent rotation of the die holder in the cylinder 14 as the mechanism is reciprocated.

An ejector spring 67 is secured to the plate 65 in any desired manner, and is turned as at 68 (see Fig. 6 of the drawings) to provide a limited passage between the stop 61 and the turned section of the spring 67, and when the sized bearings B are forced upwardly by the upward movement of the member 46 and ejector member 58, it flexes the spring 67 so that the sized stock is snapped out of the machine and into a suitable receptacle (not shown).

An air line 69 spans the opposed heads H and opens into each of the opposed cylinders 14 (see Fig. 1 of the drawings). Air freely flows from one cylinder to the other because when the ram in the one cylinder is on its outward stroke, the air in the space between the ram body and the adjacent cap 15 of the cylinder is forced through line 69 into the opposed cylinder where the ram body is on its inward stroke, and inasmuch as these ram mechanisms are in opposed relation, it will be obvious that the air is forced alternately from one cylinder to the other as the mechanism is actuated.

The mechanism can be actuated in any desired manner and from any convenient source of power, a collar 70 being connected to the source of power (not shown) and downwardly projecting legs 71 are connected to the reciprocating panel 72, nuts 73 serving to lock said collar and the legs in set position, and I shall not show or describe the mechanism for providing the reciprocating action, as they form no part of the present invention.

The operation of the head is as follows:

With the ram mechanism etc. in position as shown in Fig. 3 of the drawings, the control member 53 is actuated to permit a single pre-formed bearing or article B to roll, by gravity, from trough 62 down against stop 61, as clearly shown in broken lines in Fig. 6 of the drawings. With the bearing B in proper position in alignment with the bore 37 in the die adaptor 38, the ram 21 is actuated by the collar 70, which is connected to a source of power (not shown). The punch 22 is threaded in the inner face of the ram and as the ram moves outwardly on its work-engaging stroke, the tapered end of the punch 22 passes through bearing B to accurately size the I. D. thereof. Continued outward travel of the ram brings the inner face of said ram into engagement with the end of the die holder 23, and the

movable length sizing member 29 in which the length adaptor D is mounted, forcing the die adaptor which moves with the die holder over the bearing B to size the O. D. thereof, and the stem 36 of length adaptor D against the one end of bearing B to wedge it between the ends of the stems 36 and 45 and accurately size it to proper length. Upon the return stroke, the ram body and punch are retracted, withdrawing the punch from the stationary length adaptor, the stripper shoe 27 engaging the shoulder 25 of the die holder 23 to retract same, and the inner shoulder of the die holder engages the shouldered section 31 of the movable length sizing member to retract it as the ram moves back to original position, the bearing B being ejected by upward movement of the ejector member 58.

I wish to direct particular attention to the fact that the bearing B does not move, the punch 22, die holder 23, die adaptor 38, and movable length sizing member 29 moving with relation thereto. The loading mechanism 46 then moves upwardly, forcing the finished article outwardly between the stop 61 and the turned section 68 of the spring 67 which snaps the article into a receptacle (not shown), this movement of the loading member admitting an unfinished article simultaneously with the ejection of the sized article.

The member 46 as noted is actuated by a solenoid or other suitable means connected to the rod 41 and moves, of course, in timed relation relative to the stroke of the ram 21.

The forward movement of the member 29 (and thereby the adaptor D) upon engagement of the ram 21 with the rear end of the member 29 is and need only be slight to size the length of the bearing. When the ram 21 is retracted, the member 27 in moving rearwardly, engages the shoulder 25 to return the die holder 23 to rearward position and the shoulder 31 on the die holder 23 engages the shoulder 30 to return the member 29 and thereby the member D, rigid therein, to position. Note that the member 58 supports the bearing (Fig. 7), while the inner diameter thereof is being sized by the punch 22, and that the body of punch 22 then supports the bearing while the member 58 moves forwardly with the die holder 23 (Fig. 5). Clearly, the punch 22 will continue to support the bearing during the return stroke until after the member 58 has returned to its original position and will finally be withdrawn from the bearing to permit ejection of the bearing by the ejector 58.

From the foregoing description, it will be obvious that I have perfected a very simple, practical and relatively inexpensive, high-production mechanism for accurately sizing a bearing and parts of a similar nature.

What I claim is:

1. An apparatus for sizing pre-formed articles comprising a cylinder, a hollow ram reciprocatingly mounted therein and having a centrally disposed I. D. punch secured thereto and projecting outwardly therefrom, a bored die holder and die adaptor mounted in said cylinder and actuated by said ram, said die holder and adaptor being reciprocable in said cylinder and having predetermined, limited longitudinal travel with relation to said ram, a movable length sizing member mounted in said hollow die holder and provided with a longitudinally projecting hollow stem through which said I. D. punch extends, a guide block adjacent the one end of the cylinder, a centrally bored, stationary, length adaptor mounted in said guide block and formed with a

hollow stem disposed in longitudinal alignment with and slidably receivable in the bore in the die adaptor, means for supporting a pre-formed article in horizontal alignment with the hollow stem and the bore in the die adaptor and through which the I. D. punch travels, said punch, die adaptor, and length adaptors successively engaging said article in predetermined sequence to accurately size the I. D., the O. D. and the length of the article on the work-engaging stroke of said ram.

5 2. The combination defined in claim 1 in which the interior of the hollow ram is shouldered and the exterior of the die holder is also shouldered at spaced-apart points to permit the relative longitudinal movement of the ram with relation to the die holder.

15 3. The combination defined in claim 1 in which a stripper shoe is mounted on the open end of the ram for engaging one shouldered section of the die holder to return it to original, retracted position after it has reached the outward limit of its work-engaging stroke.

20 4. An apparatus for sizing pre-formed articles comprising a hollow cylinder, a hollow ram reciprocatingly mounted therein and having a centrally disposed I. D. punch secured to and projecting outwardly from the open end thereof, a die holder slidable in said cylinder and formed with a reduced section extending into the open end of said hollow ram, said die holder being formed with a shouldered section engageable by said ram for moving it outwardly in said cylinder at a certain point in the outward work-engaging stroke of said ram, a length sizing member mounted in said die holder and including a length adaptor formed with a hollow stem through which said punch projects, a centrally bored die adaptor mounted in the die holder, a stationary guide block adjacent to and in longitudinal alignment with said cylinder and die adaptor, a stationary length adaptor mounted in said block in alignment with the I. D. punch and through which said punch extends as the apparatus is actuated on its outward work-engaging stroke to successively size the I. D., the O. D. and the length of the pre-formed article in predetermined sequence on the work-engaging stroke of said ram.

25 5. An apparatus for sizing pre-formed articles having an opening therethrough comprising a cylinder, a hollow ram reciprocatingly mounted therein and including an I. D. punch projecting outwardly therefrom, a hollow die holder reciprocatingly mounted in the cylinder and formed with a shouldered section extending into said hollow ram, a length sizing member mounted in said die holder and provided with a hollow stem, a centrally bored die adaptor mounted in the die holder and through which the punch extends, a guide block adjacent the one end of the cylinder,

30 6. An apparatus for sizing pre-formed articles having an opening therethrough comprising a cylinder, a hollow ram reciprocatingly mounted therein and including an I. D. punch projecting outwardly therefrom, a hollow die holder reciprocatingly mounted in the cylinder and formed with a shouldered section extending into said hollow ram, a length sizing member mounted in said die holder and provided with a hollow stem, a centrally bored die adaptor mounted in the die holder and through which the punch extends, a guide block adjacent the one end of the cylinder, a stationary length adaptor mounted in said block and formed with a hollow stem in longitudinal alignment with the I. D. punch and the bore in the die adaptor and through which the punch travels on its work-engaging stroke, said punch, die adaptor, and length adaptors successively engaging said article to size it to predetermined I. D., O. D. and proper length on the outward work-engaging stroke of said ram.

35 7. The combination defined in claim 5 in which a hardened insert is provided in the one end wall of said cylinder, longitudinally disposed stationary pins bearing against said insert and

extending through the hollow ram with their opposite ends engageable with the length sizing member for limiting the return travel of said length sizing member on the return stroke of said ram.
